CLAIM

The ornamental design for the reusable plate holder, as shown and described.

DESCRIPTION

FIG. 1 is a front, elevated perspective view of the reusable plate holder showing my new design;

FIG. 2 is a frontal view of the reusable plate holder shown in FIG. 1;

FIG. 3 is a rear view of the reusable plate holder shown in FIG. 1;

FIG. 4 is a right side view of the reusable plate holder in FIG. 1;

FIG. 5 is a left side view of the reusable plate holder in FIG. 1;

FIG. 6 is a top plan view of the reusable plate holder shown in FIG. 1; and,

FIG. 7 is a bottom view of the reusable plate holder shown in FIG. 1.

The broken lines in the drawings illustrate structure that forms no part of the claim.
